SEPARABLE FINGER RING

Robert C. Marcks, Studio City, Calif., assignor to Traub Manufacturing Company, Detroit, Mich., a corporation of Michigan

Filed June 7, 1962, Ser. No. 70,459

Term of patent 14 years

(Cl. D45—10)

I claim:

The ornamental design for a separable finger ring, substantially as shown.
